CHARLES STIRIZ, OF NEW YORK, N. Y.

INTERNAL-COMBUSTION ENGINE.

1,128,913.

Specification of Letters Patent. Patented Feb. 16, 1915.

Application filed October 4, 1911. Serial No. 652,682.

To all whom it may concern:

Be it known that I, CHARLES STIRIZ, a citizen of the United States, and a resident of the city of New York, borough of Manhattan, in the county and State of New York, have invented a new and Improved Internal-Combustion Engine, of which the following is a full, clear, and exact description.

10 My invention relates to internal combustion engines, my more particular purpose being to provide such devices with an improved water jacket in which the water is caused to circulate by the conjoint action of 15 centrifugal force and difference in density between hot and cold water.

My invention also contemplates an engine made up of a plurality of units so arranged that when an explosion takes place in 20 one unit, the gases of combustion are conducted to another unit, and there mixed with steam, this mixture then expanding and doing work within the second unit.

25 My invention further comprehends various details of construction whereby the efficiency of the engine is greatly improved.

Reference is to be had to the accompanying drawings forming a part of this specification in which like characters of reference 30 indicate corresponding parts in all the views, and in which—

Figure 1 is a vertical section taken on the line 1—1 of Fig. 2, looking in the direction of the arrow, and showing the internal 35 mechanism of the primary unit; Fig. 2 is a vertical cross section on the line 2—2 of Fig. 1, looking in the direction of the arrow; Fig. 3 is a vertical section on the line 3—3 of Fig. 2, looking in the direction of 40 the arrow, and showing the mechanism of the secondary unit; Fig. 4 is a detail showing one of the cam rollers and mechanism associated therewith for operating one of the gate pistons; Fig. 5 is a detail showing the 45 valve for admitting steam to the gases of combustion.

A tubular shaft 4 is connected with a cold water pipe 5 by aid of a swivel coupling 6, and is provided with water holes 7, 8, 9, 50 the water holes 7, 8 being arranged in peripheral groups and separated by a partition 10. Encircling the shaft 4 is a stationary tube 11, and mounted upon the latter are two disks 12, 13. Supported upon these 55 disks are two cam frames 14, 15 each hav-

ing a general annular form and secured in position by aid of screw bolts 16.

A hydro-carbon supply pipe is shown at 17 and is provided with a nozzle 17^a. Mounted rigidly upon this nozzle is a ring 18 and engaging the latter is a worm 19. This worm is connected to a hand wheel 20 and is journaled within a bracket 21. The nozzle 17^a extends through the disk 12. Secured upon the disk 12 is a tube 22 provided with an air 60 hole 23. The nozzle 17^a extends into this tube 22 and is coaxial therewith. A valve 25 having generally a cylindrical form is provided with holes 24 and is revolvably mounted within the tube 22. A pipe 26 is 65 connected with the tube 22 and is disposed adjacent to the valve 25. This valve is adapted to turn step by step and in so doing brings the holes 24 successively into registry with the tube 26. The valve 25 is provided 70 with a stem 27 and mounted firmly upon this stem is a so-called "Geneva" cross 29. A cam wheel 30 is disposed adjacent to this cross and is provided with lugs 28 arranged as shown in Fig. 1, and adapted to successively turn the cross 29 and thus actuate the 75 valve 25 step by step. The valve 25 and parts immediately associated therewith together constitute a carbureter.

The pipe 26, at its outer end, is connected 80 with a wall 31 having the shape indicated in Fig. 1. This wall is integral with a ring 32 which is supported upon spokes 32^a and is provided with an inclined portion 33, the latter being integral with the wall 31, these 85 two parts together forming an abutment which receives the force of the exploding gases. This abutment is provided with my newly invented packing 34. A revolute casing 35 is provided with an inner wall 35^a 90 and an outer wall 35^b and with a passage 36 disposed between these walls. A pipe 37 communicates with this passage and also communicates with an annular passage 38 located within a hub 38^a with which the casing 35 is provided. Another pipe 39 communicates with the passage 36 and with an annular passage 40, the latter being located within the hub 38^a. The revolute casing 35 95 is partly supported upon a number of rolling bodies 41 arranged in a circle around the disks 7, 12, and constituting a ball bearing. The casing 35 is provided with two compartments 42, as will be understood from Fig. 1. In each of these compartments is a 100 105 110

spark plug 43, and adjacent to the latter is a contact 44. This contact is connected with a binding post 44^a and is adapted to be closed and opened as the casing 35 turns. 5 Two gates 45 are carried by the casing and located within the compartments 42. Each gate 45 is mounted upon a rocking shaft 46, and connected rigidly with the latter is an arm 47 carrying a roller 48. This roller 10 runs upon the cam frame 14, the latter being provided with a cam 49 extending outwardly, as will be understood from Figs. 1 and 2.

A pipe 50 extends through the ring 32 and 15 across the machine, being connected with an abutment 51 carried by a casing 51^a. This abutment is practically an extension of a ring 52. The revoluble casing 51^a is provided with two gates 53 disposed diametrically opposite each other and located in compartments 54. Each of these gates is 20 free to swing and is provided with an arm 55 carrying a roller 56 which runs upon the cam frame 15. This frame is provided with 25 a cam 15^a which periodically guides the rollers 56 outwardly and in so doing turns the gate 53.

A cam wheel 57 turns with the casing 51^a and engages a cross 58 similar to the cross 30 29 and turns the latter step by step. Connected with the cross 58 is a rotary valve 59 which is mounted within a valve casing 60 and connected with a steam pipe 61. This steam pipe taps into the tubular hub 11 and, 35 as the casing 51^a turns, is periodically brought into engagement with each hole 9. The pipe 61 terminates in a nozzle 62 which extends into the compartment 54. A pipe 63 is connected with the compartment 54 40 and serves to discharge the gases of combustion as they finally emerge from the machine. A power wheel 64 is connected rigidly with the tubular shaft 4, and is turned thereby for the purpose of transmitting 45 power from the machine.

The operation of my device is as follows: A hydro-carbon liquid, such as gasolene or kerosene, is admitted to the hydro-carbon pipe 17 and nozzle 17^a. The operator, by 50 turning the hand wheel 20, moves the nozzle 17^a to the right or left, according to Fig. 2, and thus regulates the flow of the hydro-carbon liquid by adjusting the distance of the nozzle 17^a from the adjacent portion of 55 the revoluble valve into which it extends. The carbureter is heated by the operation of the machine, and the hydro-carbon is thus vaporized. Compressed air being forced through the opening 23, the explosive mixture 60 is forced through the pipe 26 and into the explosion chamber. Each time the casing 35 makes a turn, each door 45 is opened and closed by the action of its roller 48 upon the adjacent cam frame 14 and cam 49. The 65 gate 45 is always closed, as indicated in Fig.

1, when the explosion takes place. Each gate 45, upon approaching the inclined portion 33 of the ring 32, rides outwardly upon this portion and, upon traveling around a little farther, is free to close which it does 70 under the guidance of the cam roller associated with it.

The gases of combustion pass through the pipe 50 across the machine and are admitted 75 into the compartment 54, so as to heat up their surroundings and exert a constant pressure. Here they unite with steam from the nozzle 62, this steam being discharged periodically and at the right moment to come into contact with the exhaust gases just mentioned. 80

The mixture of the exhaust gases and the steam causes rapid expansion, and this assists in driving the revoluble casing 51^a. When the gases finally escape through the pipe 63 they have completed their work. 85

Water being admitted through the pipe 5 has free circulation through the pipe 37 out into the compartment 36 of the casing 35 and back through the pipe 39 to the tube 4 from whence it makes its escape. As the 90 water, while in the compartment 36, is heated by the explosions, the difference in the specific gravity of the water thus heated and the cold water as it enters is sufficient, in connection with the action of centrifugal force, to cause the water to circulate freely; that is to say, the mere heating of the water, by slightly lessening its specific gravity, causes the machine in acting under centrifugal force to act with greater intensity upon 100 the cold water when it enters than upon the hot water already in the machine, so that the net result is a tendency upon the part of the machine, to induct the cold water and throw it to the outside, the hot water in the 105 meanwhile constantly making its escape. This tends to keep the coldest portions of the water out near the edge of the revoluble casing where the greatest heat would otherwise be developed. It also renders the circulation of the water completely automatic 110

in the sense that no pump or similar device is necessary in order to effect a good circulation. Each time the cam wheel 30 causes the cross 29 to turn a quarter of a revolution, the carbureter is actuated accordingly, being either opened or closed, as the case may be, so that the carbureter is closed whenever the engine is in condition for an 115 explosion to take place. Similarly, whenever the cam wheel 57 causes the cross 58 to turn the valve 59, this valve always stops in such position that an explosion within the explosion chamber 54 cannot force any gases of combustion through the pipe 61. 120

I do not limit myself to the particular construction here shown and described, as variations may be made therein without departing from the spirit of my invention, the scope of which is commensurate with my 130

claims. Neither do I limit myself in every instance to the use of explosions, as in some relations various other modes of propulsion may be employed, all coming within the scope of my invention.

Having thus described my invention, what I claim as new and desire to secure by Letters Patent is:—

1. An internal combustion engine comprising low and high pressure casings, an abutment in each casing, said abutments being connected together in spaced relation and mounted on the same axis, means for supplying fuel to the high pressure casing, a conduit for conducting the products of combustion from such casing to the low pressure casing, and an exhaust conduit connected with the low pressure casing.

2. An internal combustion engine comprising a shaft, high and low pressure casings connected to the shaft, abutments in the casings connected together and around which the casings rotate, a fuel supply conduit extending between the casings and communicating with the high pressure casing, a conduit extending from one abutment to the other to convey gases from the high pressure to the low pressure casing, and an exhaust conduit connected with the piston of the low pressure casing and extending therefrom between said casings.

3. An internal combustion engine comprising a shaft, high and low pressure casings connected to the shaft, abutments in the casings connected together and around which the casings rotate, a fuel supply conduit extending between the casings and communicating with the high pressure casing, a conduit extending from one piston to the

other to convey gases from the high pressure to the low pressure casing, an exhaust conduit connected with the piston of the low pressure casing and extending therefrom between said casings, and means for conducting fluid to the low pressure casing to mix with the exhaust gases from the high pressure casing.

4. An internal combustion engine comprising a shaft, high and low pressure casings connected to the shaft, abutments in the casings connected together and around which the casings rotate, a fuel supply conduit extending between the casings and communicating with the high pressure casing, a conduit extending from one piston to the other to convey gases from the high pressure to the low pressure casing, an exhaust conduit connected with the piston of the low pressure casing and extending therefrom between said casings, said shaft being hollow, and means for conducting fluid from the shaft to the low pressure casing to mix with the gases therein.

5. An internal combustion engine comprising a pair of connected rotary casings spaced apart, abutments in the casings connected together and disposed in spaced relation, a gate in each casing, and cam devices located between the casings and fixed with respect to the abutments for actuating the said gates.

In testimony whereof I have signed my name to this specification in the presence of two subscribing witnesses.

CHARLES STIRIZ.
